UNITED STATES PATENT OFFICE.

OTTO H. MEYERS, OF NEW YORK, N. Y.

FOLDING CONVERTIBLE GOCART, HIGH CHAIR, AND BABY-JUMPER.

1,378,598.

Specification of Letters Patent. Patented May 17, 1921.

Application filed April 1, 1920. Serial No. 370,551.

To all whom it may concern:

Be it known that I, OTTO H. MEYERS, a citizen of the United States, and a resident of the city of New York, (borough of Manhattan), in the county of New York and State of New York, have invented a new and Improved Folding Convertible Gocart, High Chair, and Baby-Jumper, of which the following is a full, clear, and exact description.

This invention relates to improvements in combination devices, an object of the invention being to provide an apparatus or mechanism which can by different positioning of parts perform the functions of a baby coach, a high chair and a baby jumper.

A further object is to provide a device of the character stated which can be easily and quickly manipulated to change the position of the arrangement of parts and which will efficiently perform the functions for which it is intended.

With these and other objects in view the invention consists in certain novel features of construction, and combinations and arrangements of parts as will be more fully hereinafter described and pointed out in the claims.

In the accompanying drawings—

Figure 1 is a top plan view illustrating my improved device as a gocart.

Fig. 2 is a view in longitudinal section on the line 2—2 of Fig. 1.

Fig. 3 is a fragmentary view in section on the line 3—3 of Fig. 1.

Fig. 4 is a view in vertical longitudinal section on the line 4—4 of Fig. 5, illustrating my improved device with the parts in position to form a high chair.

Fig. 5 is a view in front elevation of the device as shown in Fig. 4.

Fig. 6 is a detail perspective view of the removable bar 53.

Fig. 7 is a top plan view illustrating my improved device with the parts in position to form a baby jumper.

Fig. 8 is a view in side elevation, partly in section, of Fig. 7.

Fig. 9 is a bottom plan view showing the wheels and their supports in folded position.

Fig. 10 is a view similar to Fig. 9 showing the wheels at right angles to the base and in operative position.

1 represents a platform having on its under face a depending angular flange form-

ing a frame 2. In the ends of this frame 2 and at the sides of the frame longitudinally positioned bars 3 are pivotally mounted and limited in their pivotal movement by the side members of the frame. On these bars 60 3 forks 4 are secured and are supported by wheels 5, the latter connected to the forks by journal bolts 6 and the pairs of forks on each bar are connected by longitudinal brace rods 7. 65

The forks are maintained in vertical position by means of transverse rods 8 which are pivotally connected to the forks at one side of the platform, as indicated at 9, and are made with hooks 10 at their other ends 70 to engage eyes 11 on the forks at the other side of the platform.

A lever 12 is pivotally connected between its ends to the bottom of the platform 1 and is adapted when the wheels are in operative 75 position to be located transversely of the platform with the ends of the lever bearing against the intermediate portions of the bars 3 so that this lever and the rods 8 serve to maintain the forks 4 in upright position. 80 A sliding bolt 13 is provided on one end of the lever 12 and is adapted to engage an eye 14 on one of the bars 3 to secure the lever in this position. When the wheels are not desired for use, the rods 8 are disengaged 85 from the eyes 11 at one side of the platform and are positioned longitudinally of the platform to allow the bars 3 with their forks 4 to be folded inwardly against the bottom of the platform, as shown in Fig. 9, 90 and when in this position, the lever 12 is swung to a diagonal position to engage over the wheels at opposite corners of the platform and secure the parts in this folded position. 95

An upwardly projecting board 15 is hinged connected to the platform 1 at its rear end, as shown at 15', and side boards 16 are provided above strips 17, the latter fixed to the platform and connected by hinges 18 100 with the side boards 16.

When the device is in use as a gocart, the side boards 16 are in upright position, as shown in Figs. 1 and 2, and are made with inwardly projecting blocks 19 to support a 105 seat 20. The seat 20 is made with a back 21 and sides 22 and is secured to a sliding T-shaped frame 23, the latter mounted on a longitudinally slotted arm 24, and a sliding strap 25 is fixed to the frame 23 and moves 110

freely on the arm 24, but is adapted to be locked at any position of adjustment by means of headed set screws 26.

The arm 24 is fixed to a crossbar 27 and the latter is pivotally mounted at its ends in brackets 28 fixed to platform 1. This bar 27 provides mounting for an ornamental device 29 which, in the present instance, is shown as a horse's head. A slot 30 is provided in the bar 27 and a pivot pin 31 projects through the device 29 and is mounted in the bar to provide pivotal movement for said device. A hammer 32 is provided on the lower end of the device 29 to engage a bell 33 on the platform 1, and reins 34 are connected to the device 29 and are adapted to be manipulated by the child to sound the bell.

A tray 35 is supported on the sides 22 so that the child cannot fall off of the seat 20. A coiled spring 36 connects a forwardly projecting tongue 37 on the bar 27 with the platform 1. The back board 15 is made with an inwardly projecting block 38 to receive and support the seat as shown in Fig. 2.

Handle bars 39 are pivotally connected to the platform 1, as shown at 40, and are provided at their free ends with a handle bar 41 and at a point between their ends with a connecting bar 42 which has pivotal or rotary mounting in the handle bars. Pins 16' (Fig. 5) limit the upward forward pivotal movement of the handle bars 39.

A longitudinal bar 43 is secured to the connecting bar 42 and a chain 44 is fixed to the back board 15 and extends around under the crossbar 27 and is fixed to the longitudinal bar 43 holding the free end of said bar 43 against the handle bar 41 and supporting the handles at the proper inclination when the device is in use as a gocart as shown in Figs. 1 and 2.

Downwardly projecting pins 45 are provided on the seat 20 at the side edges thereof and project through perforated blocks 46 on the sides 16 (Fig. 3) to strengthen the structure and prevent lateral movement of the sides. An opening 47 is provided in the seat 20 for the accommodation of a pin 48 connected to a chain 49, the latter fixed to the seat back 21, but when in use as a gocart, this pin performs no function.

When the device is in use as a high chair, as shown in Figs. 4 and 5, the wheels are folded under the platform 1 as above explained, so that the platform operates as a base for the high chair. The handle bars 39 are swung to a vertical position and the pin 48 above referred to is positioned through registering openings 50 and 51 in the seat 20 and handle 41 respectively to lock the handle bars in this vertical position. When the seat is moved to an elevation to permit the handle bars to assume a vertical posi-

tion under the same, the slotted arm 24 will be at an incline, and the bar 43 constitutes a brace and is provided with a pin 52 to engage in the eye of the set screw 26 so as to secure the parts in this position. A bar 53, which constitutes a foot rest, is positioned across the frame 23 and has a recessed intermediate portion 54 to receive the frame and a pin 55 to project through the frame and hold the foot rest in proper position under the forward portion of the seat. When the device is used as a high chair, the side 16 and back 15 are folded inwardly out of the way.

When the device is used as a baby jumper, as shown in Figs. 7 and 8, the handle bars 39 are swung downwardly to a horizontal position and locked in this position by turn buttons 56 on the rear end of the platform 1, and these turn buttons also operate to hold the arms at the proper incline as shown in Fig. 2. In this use of the device the sides 16 and back 15 are also folded inwardly, but the slotted arm 24 is located in a horizontal position and supports the seat 20 at 90 the rear end thereof, the spring 36 at the forward end of the tongue 37 providing elastic support for the seat and allowing the child to move the seat upwardly and downwardly against the action of the spring, it being understood that the seat is free from any other support other than the arm 24 and its elastic pivotal mounting.

Various slight changes might be made in the general form and arrangement of parts described without departing from the invention, and hence I do not limit myself to the precise details set forth, but consider myself at liberty to make such changes and alterations as fairly fall within the spirit and scope of the appended claims.

I claim:

1. The combination with a wheeled supporting base of a mechanism of the character described, comprising a seat, a slotted arm supported on the base, a platform slidably mounted on the arm adapted to support the seat at various elevations, and means for locking the arm in various positions of adjustment, whereby the seat is supported at various elevations.

2. The combination with a wheeled supporting base of a mechanism of the character described, comprising a seat, a pair of brackets secured to the base, a slotted arm pivotally supported adjacent one end on the brackets, a platform slidably mounted upon the arm and adapted to support the seat, and means for locking the arm in various positions whereby the seat is supported at various elevations.

3. The combination with a wheeled supporting base of a mechanism of the character described, comprising a seat, a pair of brackets secured to the base, a slotted arm

pivottally supported adjacent one end on the
brackets, a platform slidably mounted on
the arm and adapted to support the seat,
means for locking the arm in various posi-
5 tions whereby the seat is supported at vari-
ous elevations, a pair of handle bars piv-
ottally secured to the base, a crosspiece on the
handle bars, and means for removably lock-
ing said seat and crosspiece together where-
10 by the handle bars form a partial support
for the seat.

4. The combination with a wheeled sup-
porting base of a mechanism of the charac-

ter described, comprising a seat, a collapsi-
ble framework hingedly connected to the 15
base, a pair of brackets secured to the base,
a slotted arm pivotally mounted in the
brackets, a platform slidably mounted on
the arm and coöperating with the collapsible
framework to support the seat at one eleva- 20
tion, and a pair of handle bars pivotally
connected to the base and adapted to coöp-
erate with the slotted arm and platform to
support the seat at another elevation well
above said collapsible framework.

OTTO H. MEYERS.
